(57) **CLAIM**

The ornamental design for a combined cellular phone pen and pen holder, as shown and described.

DESCRIPTION

FIG. 1 is a front elevational view of a combined cellular phone pen and pen holder showing my new design;

FIG. 2 is a side elevational view;

FIG. 3 is a top plan view;

FIG. 4 is a bottom plan view;

FIG. 5 is a perspective view thereof, the cellular phone depicted by means of broken lines being shown for illustrative purposes only and forming no part of the claimed design;

FIG. 6 is front elevational view of the pen shown separately for convenience of illustration;

FIG. 7 is a side elevational view of FIG. 6;

FIG. 8 is a top plan view of FIG. 6;

FIG. 9 is a bottom plan view of FIG. 6; and,

FIG. 10 is a perspective view of FIG. 6.
